UNITED STATES PATENT OFFICE.

EDWARD T. GILBERT, OF DETROIT, MICHIGAN.

DESIGN FOR A BOLT.

SPECIFICATION forming part of Design No. 35,506, dated December 31, 1901.

Application filed June 14, 1901. Serial No. 64,597. Term of patent 7 years.

To all whom it may concern:

Be it known that I, EDWARD T. GILBERT, a citizen of the United States, residing at Detroit, county of Wayne, State of Michigan, have invented and produced a new and original Design for a Bolt; and I declare the following to be a full, clear, and exact description of the same, reference being had to the accompanying drawings, which form a part of this specification.

My invention relates to a new and original design for bolts; and its object is to provide one which will be useful as well as ornamental in appearance.

The essential features of the design reside in providing the bolt beneath its head with four longitudinal outwardly-curved and downwardly-tapering triangular ribs projecting diametrically to form the four corners of a square and in forming in the shank of the bolt between said triangular ribs four longitudinal cavities or grooves, the angular bases of which lie below the periphery of the shank and continue in a straight line until they merge at their ends into the head of the bolt and the periphery of the shank by a slight bevel portion, which forms an obtuse angle with their bases and the head and periphery of the bolt, respectively.

The design is fully illustrated in the accompanying drawings, in which—

Figure 1 is a perspective view of the bolt. Fig. 2 is a cross-section on the line 2 2 of Fig. 1, and Fig. 3 is a longitudinal section of the bolt.

Referring to the drawings, A designates the shank of the bolt proper, having its lower end

screw-threaded and the upper end provided with a head A'. Upon the neck a of the shank and beneath the head A' are formed four longitudinal diametrically-arranged triangular ribs 5, 6, 7, and 8, which are curved longitudinally outward from the point where the head and shank meet to some distance beyond the periphery of the latter, from which point they taper gradually downward and merge into the periphery of the bolt. These four ribs form the four corners of a square, and the outermost sweep of the curvature of the ribs is near the upper ends thereof, causing the contour of the neck to be of essentially balloon shape. Within the shank and between the triangular ribs are formed four longitudinal grooves or cavities, represented by the numerals 1, 2, 3, and 4, which are likewise triangular in cross-section, and their angular bases fall below the periphery of the shank, which reduces the shank at this point. The ends of the cavities merge into the head and periphery of the shank by a slight bevel portion, which forms an obtuse angle with the under face of the head and the periphery of the shank, respectively.

Having thus described my invention, what I claim is—

The design for a bolt, substantially as shown and described.

In testimony whereof I sign this specification in the presence of two witnesses.

EDWARD T. GILBERT.
